CLAIM

The ornamental design for a support for flower pots, as shown.

DESCRIPTION

FIG. 1 is a side elevational view of a support for flower pots showing my new design;

FIG. 2 is a top plan view thereof;

FIG. 3 is a side elevational view, opposite that seen in FIG. 1;

FIG. 4 is a bottom plan view thereof;

FIG. 5 is a front elevational view thereof; and

FIG. 6 is a rear elevational view thereof.
